TRANSFER PRINTING FOR FIBROUS ARTICLES

Application filed July 6, 1929. Serial No. 376,493.

My invention relates to a transfer printing process whereby permanent markings of any kind can be made on fibrous articles and materials, such as paper, cloth, leather, etc. It is particularly suited and intended for decoration or ornamentation purposes.

In prior transfer-printing processes, the subject matter (i. e. lines, numerals, letters, etc.) is first printed on sheets of paper, cloth, etc. by means of some convenient printing process, and thence transferred by contact to the articles or materials ultimately desired to receive it. Herein I use the term "transfer sheet" to identify such a sheet with the subject matter printed on it. By the term "article", I refer to any article or material the marking of which is the end sought, and regardless of whether the same be a finished or partly finished manufactured article or a material for future fabrication, such as cloth in the piece, skins, etc.

According to one class of transfer printing processes, the transfer from the transfer sheet to the article is accomplished or assisted by a transfer fluid acting on the ink. The transfer sheet and the article are placed in contact in the presence of a suitable fluid, usually a liquid, pressure is applied either locally, as by rubbing, or over the whole area at once, as by squeezing in a press, and after a sufficient interval the paper base of the transfer sheet is peeled off the article, leaving more or less of the ink behind on the article. Letter-press copying of letters is a well known example of such a process. In some of these processes the coloring matter used in the ink is a dye and the transfer liquid is a solvent for the dye; it is assumed that dyeing of the fibres of the article is accomplished in some such instances. These prior known transfer printing processes are of limited application however, and are subject to various faults; bleeding for example, is hard or impossible to control, lines tending to appear blurred on the article and color gradations tending to disappear. While therefore these prior transfer printing processes are suitable for certain work, such as the production of copies of letters, and the printing of embroidery designs and identify-

ing numbers and letters, for example, they are not suited for general decorating and ornamental work under factory conditions.

The object of my invention is to improve this class of transfer printing processes to such an extent that they can be used for ornamenting and decorating fibrous articles and materials under ordinary factory conditions; or to provide a process suitable for permanently decorating and ornamenting fibrous articles and materials of various shapes, sizes and kinds under factory conditions, wherein any of a considerable range of colors can be used.

The accompanying drawing illustrates, diagrammatically, an embodiment of my invention.

According to my invention, I use, in the ink, a dyestuff rather than a pigment incapable of taking part in a dyeing action, to the end that the marking ultimately made on the article, may be made by dyeing the fibres of the article rather than by a mechanical fixation of the coloring matter to the article by means of the vehicle part of the ink, or a mere staining of the article. With the dyestuff I mix a vehicle suiting the particular printing process selected for printing the transfer sheets; that is to say, the vehicle material is so chosen that the ink resulting from the mixture has that viscosity, tacky or greasy nature, and whatever other characteristics that may be required of the ink used in the particular printing process employed for laying down the ink on the base of the transfer sheet. Furthermore, I choose for the vehicle a substance or substances that will remain on the transfer sheets until the transfers are made to the articles; I believe that the presence of the vehicle at the time the transfer is made helps to confine the dyestuff to its intended boundaries. The dyestuff is not to be held in the vehicle in solution however, but in a solid state; in suspension as it were. If the dyestuff is soluble in the vehicle, bleeding may take place in the transfer sheet and this results in blurred outlines and poor color gradations in the reproduction in the article. Furthermore, for certain colors, I have seemed to find it im-

possible to get sufficient dyestuff into the vehicle in dissolved form to give the desired color intensity in the reproduction on the article. Hence I use vehicle material or vehicle materials (including in that term everything in the ink except the dyestuff) that is not a solvent for the dyestuff, or in which at least no great part of the dyestuff is carried in solution; the dyestuff and vehicle are so chosen that the dyestuff is substantially insoluble in the vehicle. The dyestuff may be introduced initially into the vehicle in the form of a solution of the dyestuff, however, if desired, providing the solvent is evaporated, for example, or if the dyestuff is precipitated or is otherwise restored to or produced in a solid state prior to printing on the transfer sheet base; at the time of the printing of the transfer sheet however substantially all the dyestuff should be in an undissolved state and it should remain in this solid state until the transfer to the article is made. Preferably therefore I take the dyestuff in powdered form and grind it into the chosen vehicle. Afterward this mixture can be thickened if too thin, or thinned if too thick, by the addition of suitable inert substances as will be understood; also drying retardants and/or other useful substances can be incorporated in and made a part of the ink as will be understood.

With such an ink I print up the transfer sheets; that is to say, I print the subject matter on sheets of paper, cloth or other relatively light, thin, flexible material. Preferably I use a fibrous material for these transfer sheet bases, because of the permeability of fibrous materials. Newsprint paper is suitable and usually gives better results than a heavily sized paper. The transfer sheets can then be stored, and used as needed so long as the vehicle remains on the transfer sheet and remains permeable to the transfer-solvent used in making the transfer.

To make a transfer or print on the fibrous article, I take one of the transfer sheets and press it smoothly to the article, preferably with its inked face to the article, in the presence of a substance or substances which is a solvent for the dyestuff or dyestuffs or at least is a solvent for the essential active principle of the dyestuff, and which is readily permeable to (capable of entering readily) the vehicle part of the ink and capable of carrying dyestuff or its essential needed principle from well within the vehicle into dyeing relation to the fibres of the article. This substance or mixture of substances is here called the transfer-solvent. Where the dyestuff appears in the ink as a compound needing to be broken up, or which can be broken up, before its action on the fibres is accomplished (for example where the dyestuff in the ink is in the form of a lake), the transfer solvent can be employed to or act to break

up the compound; it need not then be a solvent for the dyestuff-compound found in the ink; it only need be a solvent for the dyestuff proper or essential principle; an example of this is given hereinafter. Preferably the transfer-solvent is a solvent for the vehicle part of the ink as well as a solvent for the dyestuff and permeates the vehicle because of its solubility therefor. Preferably also it is a substance in which the dyestuff or dyestuffs become relatively insoluble as the dyestuff comes into dyeing relation to the article fibres and become fixed thereto. Finally, the substance or substances for the transfer solvent is or are so chosen that it does not attack and modify the article as an article, of course, and is a substance having a high degree of capillarity so that it readily moves in between the fibres of fibrous articles as is more fully explained in a copending application of mine dealing with the application of this process to the marking of leather. Usually I apply the transfer-solvent to the article, either by spraying or dipping, immediately before making the transfer, and apply the transfer sheet dry to the wetted article; I regard this as highly desirable. Usually too I apply pressure by squeezing the transfer-sheet to the article in a press, with considerable pressure; I have used up to 300 pounds per square inch. This is not to be understood to indicate however that such high pressures as this are always necessary. Where heat does not deleteriously affect the article, heat may be used simultaneously with the pressure as by passing steam through pipes provided in the plates of the press; heat is not altogether an essential however. The transfer of dyestuff from the transfer sheet to the article takes place rather quickly, at least under high pressure, a transfer being produced in from a fraction of a minute to two minutes. At the same time the length of time the transfer sheet is left in contact with the article is not critical; that is to say, without heat I have left a transfer sheet under pressure on an article for as much as five minutes without producing noticeable bleeding or blurring. When the transfer has been accomplished, the transfer sheet is peeled off the article of course. Preferably I employ a transfer-solvent that is also volatile, so that it is readily removed or escapes from the article, by evaporation, after it has performed its function; again the alcohols serve as examples.

It will be apparent now that from a broad point of view, the exact nature of the "dyestuff" employed in the ink is not material to my invention, excepting only that it be one which causes the marking ultimately made on the article to be a marking by dyeing, as that term is used in the dyeing art, and not a mere staining or a mere fixing of pigment to the article by the vehicle of the ink after

the manner of printing. The various forms which this "dyestuff" may assume will be understood by those skilled in textile printing, who will also understand the various 5 manners in which the article may be treated either before or after the transferring is done, or both before and after, either to "prepare" the article, for cleaning, to brighten the colors, to fix the dye, etc. etc. The "dyestuff" may be a dye or dyes per se; that is to 10 say, coloring matters capable of producing color effects by a dyeing action, either with or without the aid of a mordant or fixing agent; when the dye or article demands fixing 15 agents or mordants, they may be incorporated in the inks along with the coloring matters, or they can be applied direct to the article either before or after the transferring is done, as the nature of the dyes and these 20 agents or factory practice may dictate; in a suitable case part of the agent or agents may be incorporated in the ink and part applied direct to the article. For developed colors and other stuffs acting in analogous ways 25 (e. g. indigo) all the constituents may be incorporated in the ink when the conditions are suitable, or only a part of the constituents may be incorporated in the ink and when necessary the remainder applied direct to 30 the article either before or after the transferring operation. Again the "dyestuff" incorporated in the ink may be merely a mordant or fixer for the dye, the dye itself being applied direct to the article and dyeing the 35 article where and as mordant is applied to the article. Or the "dyestuff" incorporated in the article may be a discharge, or a reserve or resist; in the first case the article being dyed all over prior to the transferring process 40 and the dye itself being discharged where and as the discharge substance is applied to the article by transferring; in the second case, the dye being applied to the article subsequent to transferring process 45 and dyeing the article where and as the applied reserve or resist permits. Particularly in these last two cases, the subject matter transferred to the article may be the reverse of the print desired on the article. Further- 50 more it will be apparent that the substance or substances mixed into the vehicle may or may not be the "dyestuff" ultimately desired to be transferred to the article, but the latter may be a reaction product. I anticipate that 55 usually it will be that dyestuff itself, but conceivably it may be a substance that later reacts, or two or more substances that react together, to produce the desired "dyestuff" or "dyestuffs". Still further, the "dyestuff" em- 60 ployed in the ink may be a pigment incapable in itself of dyeing, providing the pigment is one that can be broken up to release a dye, or one from which a dye is readily derived, by means of a substance suitable for serving as 65 or in a transfer-solvent. Lakes are examples.

The transfer-solvent need not then be a solvent for the pigment as a whole, but it must then be one serving two functions, namely deriving a dye or the essential dyeing principle from the pigment, and acting as a solvent for this essential principle. Accordingly when a lake or lakes are used as the "dyestuff" in the ink, I employ as or in the transfer-solvent a substance capable of breaking up the lake or lakes, freeing the dye or dyes, and a substance capable of dissolving the dye or dyes; a single substance may serve both functions. 70

The use of a rhodamine lake ink will serve to illustrate the operation with a lake ink as well as a specific example of my process from its broader aspect: A rhodamine lake is mixed into the ink vehicle. This rhodamine lake may be one formed by precipitating the basic dye rhodamine from a water solution thereof, by means of a resin soap and the metallic salt aluminum sulphate. The precipitated lake is filtered out and dried. In finely powdered form, the lake may then be ground into linseed oil thickened with paraffin wax to 80 such a consistency that the resulting lake-vehicle mixture has that consistency required for the operation of printing the transfer sheets. The ratio of precipitate or lake to the linseed-oil-wax vehicle is found by trial, that 85 ratio being used which gives the desired color strength or tintorial value in the reproduction on the article. With the ink thus formed, the design or ornamental matter is printed on sheets of such paper as is used for newsprint, using blocks or rolls etched or engraved in accordance with the desired design. For quite some time thereafter this ink will remain permeable to the transfer-solvent here- 90 after specified, and hence as many of the transfer sheets may be printed up at once as will be required for quite a while. When an article is to be decorated, say a piece of cloth, the cloth is sprayed with or dipped into benzine, constituting the transfer-solvent, and 95 immediately thereafter one of the transfer sheets is laid on it, inked face to the cloth, and the two pressed momentarily in a press. Considerable pressure may be used to evenly 100 and uniformly contact the transfer sheet with the cloth as before noted. The linseed oil-paraffin wax vehicle of the ink being soluble in the benzine, the benzine penetrates well into the ink immediately on this contact. The rhodamine lake is insoluble in the benzine, 105 but the single substance benzine here acts to both break up the lake and dissolve the rhodamine dye. Rhodamine therefore is carried into the fibres of the cloth by the benzine; incidentally the aluminum sulphate is left behind on the transfer sheet since it is insoluble in the benzine. After pressing the transfer sheet to the article for a moment therefore, the two are taken from the press, and the transfer sheet is peeled off the article. Rho- 110

amine is now found deposited within the article in accordance with the design as initially printed on the paper sheets. Assuming the cloth to be an animal fibre, or to have been mordanted preliminarily, this transferring operation itself dyes the design to the fibres of the cloth in rhodamine. If and as necessary, the cloth may be mordanted before the transfer is made, or after the transfer, as, for example, by spraying with tannic acid and tartar emetic as will be understood.

It will be understood from the foregoing, and especially from the description of my invention as it involves dye-lakes, that hereinafter in the claims when I use the phrase "solvent for the dyestuff" or the like, I include therein not only those substances which are solvents for the whole of a "dyestuff", but also those substances which are solvents for only the essential principles of complex dyestuffs, that is to say, those parts of complex dyestuffs that are essential to produce the desired dyeing action. In general, my invention is not limited to the details of the foregoing description except as appears herein-after in the claims.

I claim:

1. The method of making markings on fibrous articles, which consists in printing the subject matter on transfer sheet bases with ink incorporating dyestuff, substantially all of which is in an undissolved state, and vehicle material suiting the ink to the particular printing process by which the printing onto the transfer sheet bases is done, and in which said dyestuff is substantially insoluble, and pressing, while the vehicle is still present on the transfer sheets, the transfer sheets to the fibrous articles in the presence of a substance which is or contains a solvent for the dyestuff and which is capable of permeating said vehicle and carrying dyestuff therefrom into dyeing relation to the fibres of the articles.

2. The method of making markings on fibrous articles, which consists in producing an ink or inks consisting essentially of dyestuffs little or none of which is in solution and vehicle material suiting the resulting ink or inks to the particular printing process by which the subject matter is intended to be printed on the transfer sheet bases and in which said dyestuff is substantially insoluble, printing the subject matter on transfer sheet bases with said ink or inks, and pressing, while the vehicle is still present on the transfer sheets, the transfer sheets to the fibrous articles in the presence of a fluid which is or contains a solvent for said dyestuff, and which is capable of permeating said vehicle and carrying dyestuff therefrom into dyeing relation to the fibres of the articles.

3. The method of making markings on fibrous articles, which consists in printing the subject matter on transfer sheet bases permeable to the transfer fluid hereinafter

mentioned with ink incorporating dyestuff substantially all of which is in an undissolved state and, intermixed therewith, vehicle material suiting the ink to the particular printing process by which the printing onto the transfer sheet bases is done and in which said dyestuff is substantially insoluble, placing, while the vehicle is still present on the transfer sheets, the printed transfer sheets against the fibrous articles with the inked faces of the sheets to the articles, pressing the transfer sheets into firm contact with the articles in the presence of a transfer fluid which is a solvent for the dyestuff and for the vehicle and capable of carrying said dyestuff into dyeing relation to the fibres of the article, and then removing the transfer sheets from the articles.

4. The method of making markings on fibrous articles, which consists in mixing dyestuff in a solid state with vehicle material suiting the resulting ink or inks to the particular printing process by which the subject matter is intended to be printed on the transfer sheet bases and in which said dyestuff is substantially insoluble, so that at the said printing substantially none of the dyestuff exists in the vehicle in a dissolved state, printing with said ink or inks, the subject matter on transfer sheet bases which are permeable to the transfer fluid hereafter mentioned, applying, while the vehicle is still present on the transfer sheets, the printed transfer sheets against the fibrous articles with the inked faces of the sheets in contact with the fibres of the articles, pressing the transfer sheets into firm contact with the articles in the presence of a transfer fluid which is a solvent for the dyestuff and for the vehicle, which is capable of carrying said dyestuff into dyeing relation to the fibres of the article, and which does not attack the respective article, and then removing the transfer sheets from the articles.

5. The subject matter of claim 3, characterized by the fact that the transfer sheet bases used are fibrous and thereby permeable to the transfer fluid.

6. The subject matter of claim 4, characterized by the fact that the transfer sheet bases are fibrous and thereby permeable to the transfer fluid.

7. The subject matter of claim 3, characterized by the fact that the transfer fluid is applied to the articles and the transfer sheets receive transfer fluid only as and when the transfer sheets are placed against or pressed to the articles.

8. The subject matter of claim 4, characterized by the fact that the transfer fluid is applied to the articles before the transfer sheets are applied to the articles and the transfer sheets receive transfer fluid only from the articles.

9. The method of making markings on

fibrous articles, which consists in printing
the subject matter on transfer sheets bases
with ink incorporating a lake substantially
all of which is in an undissolved state and
5 vehicle material suiting the ink to the par-
ticular printing process by which the printing
onto the transfer sheet bases is done, and in
which the lake is substantially insoluble, and
10 pressing, while the vehicle is still present on
the transfer sheets, the transfer sheets to the
fibrous articles in the presence of a substance
which is capable of freeing the dye from the
lake, dissolving the dye, and permeating the
15 vehicle and carrying dye therefrom into dye-
ing relation to the fibres of the articles.

15 In testimony whereof, I have signed this
specification.
